UNITED STATES PATENT OFFICE.

FREDERICK KAIFFER, OF NEW YORK, N. Y., ASSIGNOR TO J. W. FISKE, OF SAME PLACE.

DESIGN FOR A VASE.

SPECIFICATION forming part of Design No. 16,288, dated September 22, 1885.

Application filed June 9, 1885. Term of patent 14 years.

To all whom it may concern:

Be it known that I, FREDERICK KAIFFER, of New York, in the county of New York and State of New York, have invented a Design 5 for a Vase, of which the following is a specification.

My invention consists in a novel design for an ornamental vase, as hereinafter more fully described, and as shown in the accompanying 10 photograph.

The body or bowl of the vase has around its upper edge a chamfered border, H, the lower edge of which terminates in a series of V-shaped points. Next below this border is a 15 row of ornamental leaves, C, having scroll tops extending around the bowl, and directly below them a band in the shape of a notched molding or fillet extends around the bowl. Underneath this band there is another row of 20 ornaments, which consists of tulips with berries, as shown at D, and a series of what are known as "raffle-leaves," with button-stems, as shown at E, the tulips and raffle-leaves al-

ternating in the row, as shown. At opposite sides of the bowl there is arranged a conventional stork's head, A, with a coiled serpent, B, in its bill, it also having spread wings I reaching from the neck back to the bowl, and the lower portion below the wings terminating in two ornamental scrolls, as shown, the 25 upper scroll resting against the bowl about midway of its height, and the lower scroll extending down and terminating a short distance from the shaft J, upon which the bowl is supported underneath, as shown in the accompanying photograph. The above features thus arranged upon the exterior of the vase impart to it a very rich and highly-ornamental appearance.

What I claim is—

The design for a vase, substantially as shown and described.

FREDERICK KAIFFER.
